VENDING MACHINE.

Application filed February 27, 1928. Serial No. 257,460.

Our invention relates to vending machines particularly adaptable for the dispensing of goods of a semi-soft nature such as candy, caramels and the like, although it will be clearly understood at the outset that our invention is not limited to such use and is fully capable of dispensing articles of many and various kinds and character.

Our invention is preferably of the coin controlled type, although this is not essential.

The principal object of our invention is to provide a plurality of article carriers, movable step by step to dispensing position, the articles being automatically ejected at such position.

Another object of our invention is to provide a novel cam means for controlling the feeding of the articles to dispensing position, and for ejecting them thereat.

Still another object of our invention, and an important one, lies in the arrangement and construction of the carriers or chutes for the goods to be dispensed.

Other objects and advantages in details of construction and operation will be apparent as the description now proceeds, reference being had to the accompanying drawings wherein like reference numerals indicate like parts.

In the drawings:—

Figure 1 is a side view of our improved vending machine, partly in section and certain parts being broken away for clearness of illustration.

Figure 2 is a detail view partly in section showing in plan the cam controlling or operating device.

Figure 3 is a detail cross sectional view through one of the carriers or chutes in one position with respect to the cam.

Figure 4 is a view similar to Figure 3 showing the carrier or chute in another or ejecting position with relation to the cam.

Figure 5 is a detail cross sectional view of one of these carriers or chutes.

Figure 6 is a perspective view illustrating a modified form of the chute.

The reference numeral 1 indicates a base projecting upwardly from which is an open frame 2, centrally of the upper portion 3 of which is journaled one end of a shaft 4, the opposite end of which is suitably journaled for rotation in the base 1. Secured to the shaft 4 directly above the portion 3 of the

frame, is a ratchet 5, adapted to engage with the teeth of which is a pawl 6 pivoted to said portion 3 of the frame. A coil spring 7 encircles the shaft 4, one end of such spring being anchored as at 8 to one of the cross arm supports 9 secured to the shaft 4 just below the portion 3 of the frame, and the opposite end of the spring 7 being secured in any suitable manner to the base 1. The extreme upper end of the shaft 4 is threaded as at 10 to receive a suitable key or winding device when the outside cover 11, surrounding the entire device, is withdrawn, whereby to rotate the shaft 4 and place the spring 7 under tension. This coil spring 7 therefore normally tends to urge the rotation of the shaft 4 in one direction, the same direction as the winding of the spring, for a purpose to be described.

The supporting arms 9 are shown in this case to be four in number extending outwardly from the shaft 4, although it will be understood that any desired number of such supporting arms may be provided, depending upon the size of the vending machine desired. The outer ends of these supporting arms 9 are provided with hooks or other pivot means 12 and on which are swung the upper end of the carriers or chutes indicated generally at 13. These chutes extend downwardly to a point adjacent the base 1 and are formed of two channel or three sided sections 15 and 16, the open sides thereof facing each other, the side flanges of the outer sections 15 embracing the side flanges of the inner sections 16, whereby to form a hollow chute for receiving the caramels 17 or other goods to be dispensed. The upper ends of these chute sections 15 and 16 are provided with extending ears 18, through which passes the spindle 19, the center portion of which is formed to engage with and swing from the hooks 12.

It is well known that when goods of a semi-soft character, such as candy, caramels, are stacked in columns one upon the other, the weight of the column has a tendency to cause the lowermost caramel to spread, which condition in an unyielding chute or carrier will not permit the proper feeding of the goods downwardly one at a time for dispensing. Hence, our reason for providing the chute or carrier 13 in two sections hinged together as illustrated clearly in Figure 1, the sections of which can be spread slightly apart at the lower or dispensing end in order to insure the

feeding downward of the column of caramels or other goods.

The lower end of the outer section 15 of the chute 13 is provided with an opening across its closed side, such opening being indicated at 20. The lower end of the inner section 16 is likewise provided with an opening 21 across its closed side, the openings 20 and 21 registering with each other. This inner section 16 of the chute is provided with a bottom flange 22 extending inwardly across the width of the outer section 15, whereby to provide a shelf or seat for the lowermost caramel 17 in the chute. A bottom flange 23 of the outer section 15 has projecting downwardly a roller 24 for a purpose to be described.

Secured to the shaft 4 adjacent its lower end is another set of cross arms 25 similar to the arms 9 at the upper end and extending in the same direction as such upper arms 9. These arms 25 extend outwardly to points adjacent the lower ends of the chutes 13, such arms terminating at a point flush with the opening 21 in the inner section 16, when the chute is suspended in its normal vertical position from the upper arm 9. These arms 25 are provided adjacent their outer ends with slots 26 adapted to receive guide fins 27 carried by the inner section 16. These guide fins 27, in addition to preventing twisting or lateral displacement of the chutes 13, cooperate with the closed ends of the slots 26 to limit the outer and inner swinging movements of said chutes.

Elastic means consisting of the coil springs 28 and straps 29 are provided for surrounding the chute 13 whereby to resiliently hold the sections 15 and 16 together. The resilient holding of the sections together frictionally holds the column of caramels in position in the chute and to a large extent relieves the weight of the column of caramels from those at the lower end. This elastic means 28 and 29 is readily removable to permit access to the interior of the chute sections. It should be noted also in this connection that the chutes 13 are readily removable from the machine by simply unhooking them at the top from the hooks 12 and lifting the same vertically until the fins 27 are out of the slots 26.

Also secured to the shaft 4 adjacent its lower end and extending outwardly therefrom preferably at points between the extending supporting arms 25 are stop members 30 adapted to cooperate with a pin 31 carried by an angular projection 32 extending laterally from a lever 33 pivoted between its ends as at 34 on a bracket 35. A coin chute 36 may be provided in the outer casing 11 of the machine terminating at its lower end directly over one end of the lever 33. The opposite end of this lever 33 is preferably weighted as at 37 and the angular projection 32 with the pin 31 is secured to the lever adjacent this weighted end. The pin 31 is nor-

mally in the path of the stop arms 30 due to this weighted end 37. When, however, a coin is inserted in the coin chute, and strikes the opposite end of the lever 33, the projection 32 and pin 31 will be momentarily lifted or raised and the stop arm 30 permitted to pass the pin 31 under the influence of the spring driven shaft 4. The pin 31 of course immediately drops back to normal position and engages and stops the next arm 30 when said arm reaches it. This provides an escapement mechanism for controlling by coins step by step rotation of the shaft 4 and the bringing of the chutes 13 one at a time into dispensing position. The stop arms 30 and the escapement mechanism just described are so arranged that upon each stop of the device, one of the chutes 13 with its openings 20 and 21 is directly in front of a suitable opening in the outer casing 11 to which is attached at such point a receptacle 38 for receiving the discharged caramel.

Mounted fast upon the base 1 is a cam block 39, the outer periphery of which is adapted to be followed by the rollers 24 carried by the lower ends of the sections 15 of the chutes 13. The contour of the periphery of this cam 39 is such that as the shaft 4 is rotated to move a given chute away from the dispensing position, the roller 24 of such chute will first ride outwardly from the center of the cam slightly causing the entire chute 13 to be swung slightly outwardly on its pivot. When the fin 27 of the inner section 16 of this chute, however, engages with the outer closed end 40 (see Figure 3) of the slot 26, further outward movement of this section 16 is prevented. The periphery of the cam 39, however, is such as to cause the roller 24 to continue to move outwardly a slight distance further resulting in moving the outer section 15 of the chute away from the inner section against the tension of the elastic means 28 and 29, thereby loosening the friction on the column of caramels 17 and permitting them to feed downwardly, the lowermost caramel dropping onto the shelf or lower flange 22 of the inner section 16, in position for ejection through the opening 20 when this particular chute again reaches the dispensing point or station.

When this spreading of the chute sections 15 and 16 as just described has been accomplished, the periphery of the cam 39 takes an inward path as at 42, permitting the chute sections to again close toward each other against the caramels 17 and also allows the chute itself to swing by its own weight back to vertical position in which position it remains until it reaches the ejecting or dispensing station.

Just prior to reaching the dispensing station, the roller 24 of the chute passes between the inner surface of the second cam member 43 suitably mounted on the base 1, and the outer surface of the periphery of the cam 39.

During this last stage of movement therefore of the chute to the dispensing point, the chute is guided by the slot formed by these two cams and maintained in vertical position until it reaches the dispensing point at which time the roller 24 rides inwardly upon the inwardly projecting face 44 of the cam 43 and opposite which inwardly projecting face is a recess 45 in the periphery of the cam 39, to permit such inward swinging of the roller 24 and the chute 13. Obviously this inward swinging of the lower end of the chute 13 compels the passing of the outer end of the supporting arm 25 through the openings 21 and 20 of the chute sections, resulting in the ejection of the lowermost caramel resting on the shelf or flange 22, the caramel being ejected into the receptacle 38. The fin 27 carried by the inner section 16 moves inwardly in the slot 26 during this action and engages with the closed inner end thereof to limit the movement of the chute.

The auxiliary cam 43 terminates directly beyond this dispensing station and the periphery of the cam 39 is such that the roller 24 again rides outwardly and again starts on its outward swing to the point of relieving the pressure on the caramels by spreading the chute sections to again permit the feeding of the column of caramels downwardly, as before described. Obviously this action repeats itself with each of the chutes and it will be clear that so long as the chutes contain goods to be delivered, each release of the escapement mechanism by means of a coin permits the bringing of a chute to dispensing position and automatically ejecting a caramel or other article.

Secured to the base 1 and projecting upwardly above the cams 39 and 43 and positioned just inside the outer casing 11 is a semi-circular guard 46 extending around the periphery of the cam 39 from the point at which the chutes swing back to normal vertical position, to adjacent the point at which the caramels are ejected. This guard prevents the accidental dropping out or displacement of the lowermost caramel in the chutes as they swing around to dispensing position.

In Figure 6, I have illustrated a modified type of chute construction wherein the chutes can be adjusted to caramels or articles of different lengths and likewise which, when the sections are swung apart at their lower ends, in the manner above described the tension or friction of the chute sections on the caramels will be relieved on all four sides thereof, thus insuring the proper dropping or downward feeding of the column of caramels.

In this form, the sections 15^a and 16^a are two sided only, the single side flange 47 of each engaging against the closed side of the other to form the hollow chute. These sections are hinged from corner to corner in any suitable manner as by the pintle 48 which if

varied in length will determine the length of article which can be accommodated within the chute. Obviously also when the sections 15^a and 16^a are spread by swinging them apart on the pivot 48, the spreading will be diagonal with reference to the plan of the section surfaces, thus relieving or withdrawing the support from the column of caramels on all four sides thereof.

From the foregoing, it will be seen that we have provided an automatic vending machine for candy caramels or other goods of a semi-soft nature and which is adaptable for many other kinds of goods, wherein the ejection of the articles is automatic as is the presentation of the article carriers at the ejecting station or position.

We do not limit ourselves to the specific coin controlled escapement device as obviously there are many types of such escapements adaptable to our machine. Further, we do not limit ourselves to any of the details of construction and arrangement of parts herein shown and described other than by the appended claims.

We claim:

1. A vending machine comprising article carriers movable to and from dispensing position, said carriers comprising chutes for receiving a column of articles, and means for normally maintaining frictional engagement between the inner walls of said chutes and said articles, and means for relieving said frictional engagement as said carriers move away from dispensing position to permit said column of articles to feed downwardly in said carriers.

2. A vending machine comprising article carriers movable to and from dispensing position, said carriers comprising chutes for receiving a column of articles, and means for normally maintaining frictional engagement between the inner walls of said chutes and said articles, and means for relieving said frictional engagement as said carriers move away from dispensing position to permit said column of articles to feed downwardly in said carriers, said means comprising a cam surface cooperating with said carriers.

3. A vending machine comprising article carriers movable to and from dispensing position, said carriers comprising sectional chutes for frictionally embracing a column of articles, and resilient means cooperating with said sections for normally maintaining the frictional engagement with said articles.

4. A vending machine comprising article carriers movable to and from dispensing position, said carriers comprising sectional chutes for frictionally embracing a column of articles, and resilient means cooperating with said sections for normally maintaining the frictional engagement with said articles, a cam for guiding the movement of said

chutes, and means on said chutes and cooperating with said cam for relieving said frictional engagement at one point in the movement of said chutes, whereby to permit the downward feeding of said articles in said chutes.

5. A vending machine comprising a rotatable support, article carriers swingably mounted thereon comprising independent 10 chutes, means for rotating said support to bring said chutes to dispensing position, and means including a separable connection whereby said chutes may be removed from said support.

15 6. A vending machine comprising a rotatable support, article carriers swingably mounted at one end thereon, the opposite ends of said carriers being free to swing outwardly and inwardly with respect to said support, means for guiding and limiting said swinging movement, and a cam controlling said swinging movement upon the rotation of said support.

20 7. A vending machine comprising a rotatable support, article carriers swingably mounted at their upper ends thereon, the lower ends of said carriers being free to swing outwardly and inwardly with respect to said support, said carriers comprising sectional 25 chutes frictionally engaging a column of articles therein, openings adjacent the lower ends of said chutes, a cam controlling said swinging of said chutes, and means on said chutes and cooperating with said cam whereby 30 said frictional engagement will be relieved at one point in the rotation of said support to permit the lowermost article of the column 35 to drop to a position opposite said openings, and whereby said article will be ejected through said openings at another point of rotation of said support, said support having means in position to pass through said 40 openings upon the inward swinging of said chutes, whereby to eject said lowermost article.

8. A vending machine comprising a rotatable support, article carriers swingably mounted at their upper ends thereon, the lower ends of said carriers being free to swing 45 outwardly and inwardly with respect to said support, said carriers comprising sectional chutes frictionally engaging a column of articles therein, openings adjacent the lower ends of said chutes, a cam controlling said 50 swinging of said chutes, and means on said chutes and cooperating with said cam whereby said frictional engagement will be relieved at one point in the rotation of said support to permit the lowermost article of the column 55 to drop to a position opposite said openings, and whereby said article will be ejected through said openings at another point of rotation of said support, said support having means in position to pass through said 60 openings upon the inward swinging of said chutes, whereby to eject said lowermost article.

9. A vending machine including a series of article carriers movable to and from dispensing position, said article carriers comprising chutes composed of pivoted sections the inner walls of which are adapted to frictionally engage a column of articles therein, resilient means for normally holding said 65 sections in such frictional engagement, and cam controlled means, operative upon movement of said carriers, for relieving said engagement on all sides of said articles to permit the downward feeding of said articles to 70 dispensing position.
